CONVEYOR SLAT SECUREMENT

Harry L. Cohen, New York, N. Y., assignor to
S & S Corrugated Paper Machinery Co. Inc.,
Brooklyn, N. Y., a corporation of New York

Application April 2, 1946, Serial No. 659,117

3 Claims. (Cl. 198—175)

1

My present invention relates to sheet feeding mechanism and more specifically to a type of sheet feeding mechanism wherein a slat or plurality of slats are mounted across drive members such as chains moving along the plane of a table on which successive blanks are to be fed through specific apparatus which performs various operations on the blank.

Thus, by way of example, in taping machines for taping the seams of folded cartons, it is necessary to feed the folded cartons successively through the taping machine in order that the tape may be applied.

Specific feeding mechanism may be used to eject the cartons successively from the bottom of a stack and thereafter the cartons may be moved along with respect to the taping mechanism by slats of the above mentioned type; or slats of the above mentioned type may be used first to eject blanks successively from the bottom of the stack and secondly to feed the blanks successively past the tape applying apparatus whereby they may be controlled in their movement during the taping operation.

In the construction of such slats it frequently becomes necessary to replace the slats on the drive chain in different spaced relations. Thus, where very short blanks are being fed through a specific machine such as a taping machine and it becomes necessary to set up the taping machine once more to take extra long blanks the slats must be removed and replaced for cooperation with the extra long blanks. Thus it becomes necessary to arrange a simplified means for securing and disconnecting the slats on the drive chains in a simple and easily operable manner.

Accordingly, a primary object of my invention is the provision of novel feed means for feeding blanks with respect to a machine on which operations are to be performed with respect to the blanks.

Another object of my invention is the provision of simplified feed slat securing means for securing the slats to a drive chain and for readily removing the slats from the drive chain.

Specifically, my invention contemplates mounting a pair of pins adjacent either end of the slat, or rather on that specific portion of the slat which cooperates with the drive chain or chains, and providing simplified locking means on the chain or chains for integrating the elements of the slat with the chains.

The foregoing and many other objects of my invention will become apparent in the following description and drawings in which

2

Figure 1 is a general view of a type of machine known as a taping machine embodying the slat securing members of my invention.

Figure 2 is an enlarged view in schematic perspective showing the manner in which the novel slats of my invention may readily be secured to and removed from the drive chains therefor.

Figure 3 is a view partly in cross-section taken on line 3—3 of Figure 2 looking in the direction of the arrows.

Figure 4 is a view partly in cross-section taken on line 4—4 of Figure 3 looking in the direction of the arrows.

Figure 5 is a fragmentary view in perspective showing the latching pin on one of the slats.

Referring now to Figure 1, I have here shown my novel device embodied in a taping machine mounted on a frame and having a drive motor 12 connected by an appropriate pulley 13 and belt 14 to pulley 15 which in turn is connected by belt 16 to pulleys 11 of chain sprockets 18; the chain sprockets 18 being mounted on opposite sides of the machine on shaft 19 driven by pulley 17. Pulley 15 also has auxiliary pulley 20 keyed thereto which through belt 21 drives pulley 22 which in turn drives the feed out belt 23. The taping machine is provided with other feed rollers 25 and feed out belts 26, the rollers and belts being driven by appropriate connections to the principal pulley 15 or to the motor 12. The sprockets 18 drive the chains 30 in the direction indicated by the arrow 31, the chain 30 being kept taut by the idling sprockets 32. Chains 30, as shown in Figures 1 and 2, are provided at spaced intervals with latch members 35, said latch members 35 being in registry with each other at opposite chains and carrying a slat 36 between them.

The blanks or cartons 40 which are to be taped are placed in a stack 41 between the vertical slats 42 and against the front guide slats 43. Front guide slats 43 are spaced above the bed of the machine at 44 so that one blank at a time, the bottom blank in the stack, may be fed out from the stack.

Slats 36, as they come around toward the left with respect to Figure 1, each engage a bottom blank or folded carton of the stack 41 and feed the blanks out, with respect to the taping machine. The taping machine may be of the type generally described in application of Albert F. Shields, Serial #391,701, issued November 7, 1944, as Patent No. 2,362,413, and the apparatus for applying the tape is indicated generally in the box 45. Any suitable taping apparatus may be used

for this purpose, the essence of the invention being in the slat securement and operation.

The slats may be so arranged that they actually engage the blank only after the blank has been ejected from stack 41 and separate kick feeder means may be used to eject successive blanks from the stack 41, or the slats 36 may, as shown, be used to feed out the blanks from the stack as well as to feed the blanks along through the machine.

As previously pointed out, the slats must be so arranged that they may readily be mounted on and removed from the chain so that appropriate spacing of the slats may be obtained for variations in the length of sheets which are to be operated on by the machine.

Thus, for a run of relatively short blanks or sheets the slats should be spaced very close together; whereas for a run of very long blanks or sheets alternate slats or pairs of alternate slats may be removed to provide for appropriate spacing.

Accordingly, it becomes necessary to arrange the slats in such a manner that they may readily be attached to and removed from the chains. For this reason each of the slats as is shown in Figure 5 is provided adjacent each end thereof, at the portions of the slat registering with each of the chains, with a downwardly depending latching pin 50. The latching pin 50 has the chamfered surface 51 to enable it to move readily past the latching device hereinafter described and has the snap-lock slot 52 to cooperate with the latch member 35 (shown more specifically in Figures 3 and 4) which is located at spaced intervals along the chain.

Each of the latch members 35 consists of a plate 60 attached by pins 61 and 62 to the chain 30. Pins 61 and 62 replace the regular pins of the links of chain 30 at that point and the pins 61 and 62 are threaded as shown at 63, 63 to enter into appropriate tapped openings in the plate 60.

The pins may be secured in appropriate relation to the chain in any suitable manner as for instance by cotter pins passing through openings 65, 65 thereof.

The latching plate 60 extends outwardly from the side of chain 30 and thus does not interfere in any way with the operation of the chain 30 with respect to sprockets 18 and 32.

Each of the latching plates 60 is provided with a vertical hole 70 to receive the pin 50 of the slat 36. Each of the plates 60 is also provided with a horizontal slot or recess 72 in which is pivotally mounted the latch member 73. The said latch member 73 being rotatably carried on the pin 74 which passes through the recess 72. The recess 72 is sufficiently deep so that the latch 73 may enter and cover part of the hole 70 as shown particularly in Figure 4; thus the latch 73 may readily enter into the milled slot 52 of the pin 50 of slat 36 in order to retain the pin 50 and hence slat 36 in tight engagement with the latch plate 60 as shown particularly in Figure 3.

The latching plate 60 is also provided with a recess 76 in which tension spring 77 is mounted, one end of tension spring 77 being connected at 78 to the outer end of latch 73 and the opposite end of tension spring being connected to lug 79 carried by screw 80 which is received in an appropriate threaded opening 81 of the latching plate 60. The latch 73 is biased in a counter-clockwise direction with respect to Figure 4 so

that it enters into the mill slot 52 of pin 50 in order to retain the slat position.

As above pointed out latch members 35 are mounted parallel to each other on opposite chains so that the slats 36 are carried between them. The bed 90 of the machine is provided with recesses 91 and 92 as shown in Figure 2 through which the chains 30 travel. The recesses 91 and 92 are each provided with upper extension plates 93 and 94 extending partly over the recesses. The slats 36 are each provided re-entrant channel-like lugs 95, 95 engaging the upper plates 93, 94. This holds the slats down tightly against the bed 90 of the machine and prevents them from moving up over the blanks or cartons which are being fed through the machine so that they are always in engagement with the blanks or cartons on the machine. The plates 93, 94 and the bed of the machine 90 terminate just before sprocket 18 of Figure 1, so that the slat lugs 95, 95 may slide off the plate 93, 94 to permit the slats to move with the chain around the sprocket 18.

Thus, when it is desired to place the slats on the chain 30, the operator places the slats on the chain as the latches move opposite the sprockets 18 and the lugs 95 can clear the plates 93, 94. The operator then moves the chains around until the next set of lugs to which he desires to attach a slat appear opposite the sprockets 18 and then he snaps the slats in. These operations are pursued successively until all the slats are mounted.

When it is now desired to change to a size which is greater than the size previously operated on, the operator pulls out the opposite latch members 73 for the slat which is opposite the sprocket 18 and removes the slat. He then moves the machine until the next slat which he desires to remove is opposite the sprocket 18 and removes that slat also.

By this means therefore, the operator may readily place and remove slats from the apparatus. Placing the slats in the apparatus only requires pushing pins 50 into the opening 70. The chamfered portion 51 of the pin 50 moves past the latch 73 and pushes it out or clockwise with respect to Figure 4. When the milled slot 52 appears opposite the latch 73 then the spring 77 snaps the latch 73 back into latching position. Similarly to remove the slat it is only necessary to pull the latch 73 clockwise and thus disengage the latch from the milled slot 52, so that the slat may be removed. Even an unskilled or untrained operator may thus readily place and remove slats on a machine in appropriate spaced relation for the particular size blanks or cartons which are to be operated on in the particular run. The slats are simple straight bars which are held down in order to feed the blanks forward and the latch members are simple locking members which cooperate with the milled pins of the slat. Accordingly complex securing and removal operations are avoided and a structure which is easy to manufacture, fool-proof in use and which is sturdy and not easily bent or damaged, is provided so that the means for feeding the blanks or cartons through the machine may readily be adjusted for runs of different size cartons.

In the foregoing I have described my invention solely in connection with a preferred illustrative embodiment thereof. Since many variations and modifications of my invention should now be obvious to those skilled in the art, I prefer to be bound not by the specific disclosure herein contained, but only by the appended claims.

I claim:

1. Blank moving means comprising a moving chain and a slat removably secured thereto; said slat having an extension depending therefrom; said chain carrying a latch member; said latch member comprising a plate; an opening in said plate to receive said extension; a lock member movable into said opening; and a recess in said extension to receive said lock member; means biasing said lock member into said opening; said lock member being manually removable from said opening; said lock member comprising a lever; a recess in said plate; said lever being pivotally mounted in said recess for movement in a plane normal to the axis of said opening.

2. Blank moving means comprising a moving chain and a slat removably secured thereto; said slat having an extension depending therefrom; said chain carrying a latch member; said latch member comprising a plate; an opening in said plate to receive said extension; a lock member movable into said opening; and a recess in said extension to receive said lock member; means biasing said lock member into said opening; said lock member being manually removable from said opening; said lock member comprising a lever; a recess in said plate; said lever being pivotally mounted in said recess for movement in a plane normal to the axis of said opening, an additional

recess in said plate; said biasing means being mounted in said recess.

3. Blank moving means comprising a moving chain and slat removably secured thereto; said slat having an extension depending therefrom; said chain carrying a latch member; said latch member comprising a plate; an opening in said plate to receive said extension; a lock member movable into said opening; and a recess in said extension to receive said lock member; means biasing said lock member into said opening; said lock member being manually removable from said opening, the free end of said extension being shaped to move said lock member out of said opening as it enters the opening; said biasing means snapping said lock member into said recess of said extension as said recess moves opposite the lock member.
